VEHICLE DOOR LOCK

Edward E. Kuethe, Rockford, Minn.

Application March 23, 1939, Serial No. 263,692

2 Claims. (Cl. 292—254)

My present invention relates to door locks and has for its particular object the provision of an improved lock for the doors of vehicles such as automobiles.

Generally stated the invention consists of novel devices, combination of devices and arrangement of parts hereinafter described and defined in the claims.

The various advantages of the improved lock will appear in the description of the invention illustrated in the accompanying drawing wherein like characters indicate like parts throughout the several views.

Referring to the drawing:

Fig. 1 is a fragmentary perspective showing the lock mechanism applied to the door and frame of an automobile;

Fig. 2 is a horizontal section taken through the lock approximately on the line 2—2 of Fig. 1, and with the door closed;

Fig. 3 is a perspective view showing that part of the lock mechanism that is to be applied to the door removed from the door;

Fig. 4 is a perspective view showing the mechanism of Fig. 3 looking at the same from the rear of the lock enclosing box, some parts being broken away;

Fig. 5 is a section taken on the line 5—5 of Fig. 2;

Fig. 6 is a view corresponding to Fig. 2 but illustrating a somewhat modified structure; and

Fig. 7 is a perspective view with some parts sectioned showing that part of the mechanism that is to be applied to the door removed from the door.

In Figs. 1, 2 and 6, the numeral 10 indicates one of the front doors of the automobile, and the numeral 11 indicates the co-operating door frame.

Except as hereinafter noted, the door in the frame may be assumed to be of standard auto construction in which outer flange 12 of the door is normally stopped against a rubber buffer 13 secured in the door frame. The numerals 14 and 15 indicate inside upholstery or lining secured to the inner faces of door and frame in such a manner as to form a tight joint when the door is closed.

For the application of the lock mechanism to the door and to the door frame box, light sheet metal casings 16 and 17 are set into and rigidly secured within the co-operating edges of the door and frame. The lock casings 16 and 17 are metallic box-like structures welded or otherwise secured respectively to the metallic parts of

the door 10 and casing or frame 11. The said casings are open at their adjacent faces and come close together when the door is closed.

In this improved lock mechanism the latch is in the door casing or frame structure and the co-operating mechanism is in the door frame. The latch-acting dog 18 in this improved structure is pivoted at 19 to the casing 17, and at its free end is provided with a laterally projecting blade 20 that terminates in a stop flange 21 that is engageable with a stop flange 22 on the casing 17 to limit the outward movement of the latch dog to a position slightly farther outward than shown in Fig. 2. The latch dog 18 is yieldingly pressed outward by a quite strong spring 23 of 15 the sear or U-shaped type interposed between the same and the back flange of the casing 17.

Mounted in the casing 16, as close as is practical to that corner thereof that is adjacent to the inner part of the joint between the door and frame, is a latch-retracted detent 24 in the form of a roller freely journaled to the top and bottom flanges of the said casing 16. Also pivoted in the casing 16 is a latch-retracting lever or element 25, the free end of which is engageable with the free edge portion of the latch dog 18, but which is yieldingly retracted or pressed away from said latch by a suitable spring such as a light leaf spring 26 anchored to said casing 16.

So far described, the structure illustrated in Figs. 1 to 5 inclusive is like that illustrated in Figs. 6 and 7; however, the preferred structure is illustrated in Figs. 1 to 5 and is as follows. Working through a slot in the casing 16 is a latch-releasing bar or plunger 27, the extreme outer end of which is shown as terminated in a flange 28, and the inner end of which is connected to a short crank arm 29 carried by the shaft 30 of an inside actuating handle 31.

For releasing the latch from the outer side of the door, there is an outer handle 32 having a shaft 33 journaled in the side of the door and in bearings on the casing 16, and provided with a cam-actuating arm or eccentric 34, see particularly Figs. 2 and 5, the depending end of which directly engages the flange 28 of the link 27. Here it should be noted that the shaft 33 is extended through a clearance slot 35 in the link 27.

The construction of the latch mechanism illustrated in Figs. 1 to 5 is as follows. When the door is moved from an open to a closed position, the abutment-acting roller 24 will engage the oblique face of the latch dog 18 and cam the same into the casing 17. When the roller 24

passes the free end or edge of the dog 18, the laterally extended flange 20 of said latch dog will be sprung into engagement with the roller and, under the action of spring 23, will exert force, pressing the door to a tightly closed position with the shoulder 12 engaged with the buffer 13 and the joint between the elements 14 and 15 tightly closed. Under the action just described, not only is the door tightly closed, but 10 it is also held against rattling.

To release the latch for door-opening position from the interior of the car, it is only necessary to press upward on the inside handle 31, thereby causing link 27 to press lever 25 against the 15 latch dog 18 thereby forcing the latter beyond the roller 24 so that the door may be freely opened. The same releasing action will be produced by pressing downward on the outside lever 32 which, in this instance, will cause the cam 20 arm or eccentric 34, acting through lever or arm 25, to press latch dog 18 to releasing position.

In the structure illustrated in Figs. 6 and 7, link 27' is substituted for the link 27, and this link in its outer end, is pivoted to the depending 25 crank arm 29' of the shaft 30' of the inside handle 31'. The outside handle 38, in this instance, is pivoted at 39 to a bearing 40 on the outer side of the door, and at an eccentric point, is connected to a link 41, the inner end of which 30 is shown as connected to a small bell crank lever 42 pivoted within the casing 16 and connected to the link 27' by a slot and pin connection 43. In this modified structure the operation of releasing the latch by manipulation of the inside 35 handle is the same as already described. However, the handle 38 works somewhat differently from the handle 32 in that the former will cause releasing of the latch dog when the free end is simply pulled directly outward or away from the door.

40 In lock or latch mechanism of the kind described the use of oil or grease is neither necessary or desirable. The roller acts on the latch dog with so little friction that grease is not necessary. Grease is objectionable because it runs 45 on to the edges of the door and door frame and exposed portions of the latch mechanism and, as used in the ordinary lock, soils the clothes of persons entering or leaving the car. Moreover, the latch mechanism operates very silently and insures latching the door in a properly closed 50 position. Also, the releasing of the latch for opening the door may be performed with very slight effort yet, when the door is closed, it will be held very securely against accidental opening movement.

From the foregoing it will be understood that the mechanism described is capable of modifications other than those illustrated all within the scope of the invention herein disclosed and claimed.

From the foregoing it is also evident that the lock or latch mechanism may be used on various doors other than those of automobiles or motor propelled vehicles.

What I claim is:

1. The combination with a door and a frame in which said door is hingedly mounted, of a lock mechanism involving an outwardly spring-pressed latch dog pivotally mounted in said door frame, and said dog having an approximately L-shaped operative face normally projecting outward of the door frame, a detent in the form of a roller mounted in the door at the free edge thereof closely adjacent to the inner face of the door, said roller having an entirely rolling action relative to the latch dog, whereby the door is entirely free from the friction of a sliding movement, said roller having a rolling action on the L-shaped face of said dog and movable to a position beyond said dog when the door is closed, and connections on the door for retracting said dog, said spring-pressed latch dog, when in a door-latching position, is stopped against said roller and exerts a force pressing the door tightly to closed position, and in addition to its latching function, holds the door against rattling. 30

2. The combination with a door and a frame in which said door is hingedly mounted, of a lock mechanism involving an outwardly spring-pressed latch dog pivotally mounted in said door frame, and said dog having an approximately L-shaped operative face normally projecting outward of the door frame, a detent in the form of a roller mounted in the door at the free edge thereof closely adjacent to the inner face of the door, said roller having an entirely rolling action relative to the latch dog, whereby the door is entirely free from the friction of a sliding movement, said roller having a rolling action on the L-shaped face of said dog and movable to a position beyond said dog when the door is closed, and connections for retracting said dog, said spring-pressed latch dog, when in a door-latching position, is stopped against said roller and exerts a force pressing the door tightly to closed position, and in addition to its latching function, holds the door against rattling. 40
